EVAPORATOR OF SHEETS OF DIFFERENT MATERIALS

Jules N. Saler, Springfield, Mass., assignor to Westinghouse Electric & Manufacturing Company, East Pittsburgh, Pa., a corporation of Pennsylvania

Application January 12, 1935, Serial No. 1,484

6 Claims. (Cl. 62—126)

My invention relates to evaporators for mechanical refrigerators and particularly to evaporators fabricated from sheet metal and it has for an object to provide an evaporator of this type which has better operating characteristics and is better constructed than those heretofore provided.

This and other objects are effected by my invention, as will be apparent from the following description and claims taken in accordance with the accompanying drawing, forming a part of this application, in which:

Fig. 1 is a view, in elevation, of a refrigerator equipped with one form of evaporator constructed in accordance with my invention;

Fig. 2 is a section taken on the line II—II of Fig. 3 showing the trays in elevation; and

Fig. 3 is a view, partly in side elevation and partly in section, of the evaporator shown in Figs. 1 and 2.

Referring now to Fig. 1, I show a refrigerator cabinet 10 embodying an upper machinery compartment 11 and a lower food storage compartment 12. Disposed within the food storage compartment 12 is an evaporator 13 of the sheet metal type.

Referring now to Figs. 2 and 3, the evaporator 13 comprises, essentially, an inner sheet of metal 14 and outer sheet of metal 15. The outer sheet 15 is preferably corrugated, as at 16, to provide suitable channel spaces 17 for containing refrigerant fluid. The inner and outer metal sheets 14 and 15 are usually bent, such as shown particularly in Fig. 2, to a substantially U-shaped formation to form an internal space 18 generally referred to as a sharp freezing chamber. The upper ends of each of the sheet metal sheets have complementary, semi-cylindrical header portions 19 stamped therein and extending longitudinally to form headers 21 communicating freely with the upper ends of the channel spaces 17. A suitable cross header 22 may be provided, which cross header extends transversely between the longitudinal headers 21 and communicates therewith.

Refrigerant liquid to be evaporated is supplied to the lower portion of the evaporator through a liquid supply conduit 23, which extends through one of the headers 21 and one of the channel spaces 17 to a longitudinally-extending distributing header 20 stamped in the outer sheet 15 and freely communicating with the respective channel space 17. Refrigerant vapor generated in the evaporator by the absorption of heat through the inner and outer sheets is removed

through an outlet 24 preferably connecting with the cross header 22.

The inner metal sheet 14 and the outer metal sheet 15 are preferably secured to each other by some process such as welding or brazing in 5 order to form a single, autogenous evaporator structure. In the present embodiment, I prefer to secure the sheets to each other by arc welding, in which case the boundaries or marginal portions 25 are secured to each other by a continuous weld while additional welds 26 are located between the corrugations 16.

Disposed within the sharp freezing chamber 18 are suitable ice tray supports 27 upon which are located ice trays 28 for containing water or 15 other substances to be congealed. Ice trays are also located on the horizontal surface of the inner evaporator sheet 14.

In operation, the evaporator absorbs heat from the refrigerator cabinet through its outer sheet 20 15 and absorbs heat from the sharp freezing chamber through the inner sheet 14. The vapor generated in the evaporator incident to the absorption of heat is withdrawn through the conduit 24 while make-up refrigerant liquid is supplied through the conduit 23.

Evaporators of this character must, of necessity, perform two functions, first, absorb heat through the outer metal sheet from the refrigerator cabinet so as to maintain the latter at a 30 refrigerated temperature above freezing, such as, for example, 45° F., and secondly, absorb heat through the inner metal sheet from the sharp freezing chamber so as to maintain the latter at a sub-freezing temperature in order that ice may be 35 formed in the ice trays and, when formed, maintained.

Heretofore, it has been customary, in fabricating evaporators of the type such as shown in Figs. 2 and 3, to employ inner and outer sheets 40 14 and 15 of the same kind of metal so that, consequently, the inner and outer evaporator sheets have the same coefficient of heat conductivity. Some evaporators have employed stainless steel for both the inner and outer sheets. Others have 45 employed carbon steel or silicon bronze or brass for both the inner and outer sheets.

I have, however, conceived the idea of employing metals of relatively different heat conductivities, respectively, for the inner and outer 50 sheets. For example, I may employ a metal of relatively high heat conductivity, such as brass, for the inner sheet 14 and a metal of relatively low heat conductivity such as, for example, silicon bronze for the outer metal sheet 15. I have 55

found that, by employing different metals such as suggested, arc welding of the two sheets to each other at the numerous places required, is greatly facilitated and, at the same time, a stronger weld is produced. The performance of the evaporator is also improved because there is minimum resistance to the flow of heat from the ice trays through the inner sheet 14 to the refrigerant fluid while there is relatively greater resistance to the flow of heat from the refrigerator cabinet through the outer wrapper sheet 15. As a result of this difference in conductivities, the single temperature of the refrigerant contained in the evaporator can better maintain the relatively different temperatures required in the food compartment and in the quick freezing chamber.

In addition to the specific materials mentioned, it is within the purview of my invention to employ stainless steel, Monel metal or nickel silver alloys for the outside sheet and to employ, for the inner sheet, a metal of relatively higher thermal conductivity such as, for example, carbon steel. Then again, I may employ similar metals for both the inner and outer sheets but obtain equivalent results by coating the outer sheet with a material such as, for example, rubber or enamel while conserving the thermal conductivity of the inner sheet in order that the thermal conductivity of the outer sheet may be less than that of the inner sheet.

While I have shown my invention in but one form, it will be obvious to those skilled in the art that it is not so limited, but is susceptible of various other changes and modifications without departing from the spirit thereof, and I desire, therefore, that only such limitations shall be placed thereupon as are imposed by the prior art or as are set forth in the appended claims.

What I claim is:

1. Heat-absorbing apparatus for a refrigerator embodying two sheets of metal secured to each other and forming a chamber for refrigerant liquid to be vaporized, one of said sheets of metal having a relatively higher thermal conductivity than the other sheet.

2. Heat-absorbing apparatus for a refrigerator embodying an inner sheet and an outer sheet

having portions secured to each other, said inner sheet forming a freezing chamber and said outer sheet forming, with the inner sheet, a chamber for refrigerant liquid to be vaporized, said inner sheet having a relatively higher thermal conductivity than the outer sheet.

3. Heat-absorbing apparatus, as claimed in claim 2, wherein the inner sheet is composed of brass and the outer sheet is composed of bronze.

4. Apparatus for absorbing heat from a refrigerator cabinet embodying two, nested, sheet metal shells having portions autogenously secured to each other and other portions spaced from each other so as to form a chamber for refrigerant liquid to be vaporized, said inner shell defining a freezing chamber and said inner shell having a higher thermal conductivity than the outer shell.

5. A heat-absorbing unit for refrigerating apparatus comprising a sheet metal casing so arranged as to form a freezing compartment for the reception of articles to be frozen, a second sheet metal casing disposed around the first casing and having a portion of its surface in contact with the first casing and having the remaining portion of its surface spaced therefrom, means for securing one of said casings at its periphery to the other of said casings to provide a closed chamber for containing refrigerant fluid, and means for securing the casings to each other at intermediate contacting portions, said first and second casings being composed of relatively different metals and said first casing having a relatively higher thermal conductivity than said second casing.

6. In a heat-absorbing element for a refrigerator cabinet, the combination of spaced sheet metal members having a heat-absorbing fluid circulating therebetween, means located on one side of said spaced members for congealing liquids and means located on the opposite side of said spaced members for storing foods, the sheet metal member adjacent the liquid congealing means having a relatively higher heat conductivity than the sheet metal member adjacent the food storage means.

JULES N. SALER.
